DRAFTING APPARATUS

Charles Morton, Pawtucket, R. I.

Application April 11, 1938, Serial No. 201,412

3 Claims. (Cl. 19—130)

This invention relates to an apparatus for drafting textile fibers; and has for one of its objects to provide an arrangement of the draft rolls whereby the spacing between the nip of the back rolls and the nip of the front rolls may be considerably reduced in extent.

Another object of the invention is to provide a stronger yarn by this rearrangement of the operating parts and thus a better quality of the product.

Another object of the invention is to provide a simple rearrangement of the operating parts from that adopted on drafting frames which are already in existence.

Another object of the invention is to eliminate the necessity of providing for breaker draft rolls for operation prior to the main drafting span.

With these and other objects in view, the invention consists of certain novel features of construction, as will be more fully described, and particularly pointed out in the appended claims.

In the accompanying drawing:

Fig. 1 is a sectional view through the frame showing the roll stand and weighting means;

Fig. 2 is a top plan view of a fragmental portion of the frame at one end;

Fig. 3 is an elevation of one of the upper back draft rolls;

Fig. 4 is a sectional view of this roll and showing the same as engaging the roller bearer support therefor.

Drafting apparatus for textile fibers usually comprise a pair of back draft rolls and a pair of front draft rolls with intermediate carrying rolls, there being no weight upon the carrier rolls and thus no nipping action performed on the fibers by them. In other cases there may be a pair of front rolls, a pair of nip rolls back of these front rolls between which and the front pair the main draft occurs, and then a pair of breaker draft nip rolls still further back. Also, usually the top rolls are provided in pairs with trunnions to fit into slots in an overarm to be guided in their movement, this being true whether they are loaded or whether they are merely carrier rolls. These trunnions provide friction retarding the rotation of the rolls while guiding them in their location or position. By the arrangement which I have now provided, but two nips of the yarn are had, and I provide a carrier roll between the nips acting on the same lower roll which provides the nip of the back pair of rolls, and have eliminated breaker draft rolls; and I have arranged a roller bearer for the upper back roll so that it is unnecessary for this roll to have any

trunnions to guide it in its desired position. Thus, it is of freer rotation, and by this arrangement the nips for causing the drafting are closer together so that the device is well adapted for drafting short staple cotton; and the following is a more detailed description of the present embodiment of this invention, illustrating the preferred means by which these advantageous results may be accomplished:

With reference to the drawing, 10 designates the support for the roll stand 11 which provides bearings for the group of draft rolls, there being a lower front driven roll 12 and its companion upper front roll 13 of the usual construction. Cooperating with this pair of rolls there is a lower back driven roll 14 and the upper back roll 15. A roller bearer 16 will be driven at the same speed as the roll 14 and in close proximity thereto and thus although there may be a nip at the points of contact of the roll 15 with the bearer 16 as well as the point of contact with the roll 14, as these are driven at the same rate of speed, the nip at the point of contact of the rolls 15 and 16 will be immaterial and of no functioning effect. A carrier roll 17 also engages the roll 14 that the yarn may have a shorter span from the back pair of rolls to the front pair of rolls in traveling through the machine.

The front line of driven rolls is operated through shaft 18 which is suitably rotated from some source. A gear 19 is provided on this shaft which provides drive through the train of gears 20, 21 and 22 and thence through shaft 23 to gear 24 which in turn drives the gears 25 on the end of the roller bearer 16 and 26 on the end of the back lower draft roll 14, driving them in unison in the same direction, and as they are of the same diameter they rotate at the same surface speed.

The overarms as indicated at 27 are provided with slots 28 for receiving the trunnions 29 of the upper front rolls 13, while similar slots are provided for trunnions 30 of the carrier roll 17. No such slots are provided, however, for the upper back roll 15 of Fig. 3, which, as usual, with upper rolls is formed in two sections 15a and 15b with a smaller connecting portion 31 between the sections. The ends of the roll are rounded as at 32 and are trunnionless. A saddle 33 has a recess as at 34 for the front rolls and as at 35 to fit the connecting portion 31 of the upper back rolls, which saddle is loaded by means of the link 36 engaging the lever 37 which is pivoted as at 38 on the adjustable support 39 and weighted through hanging weight 40 at some location 55.

along the lever by means of hanger 42. The link 36 may be adjusted as at 43 at its connection with the saddle. By this arrangement the upper back roll is forced toward the lower back roll 14 and supported by the roller bearer 16 so that the yarn as it passes between these rolls is nipped at 44 and then again nipped at 45 which provides the length of nip on the yarn which is usually just a little longer than the length of staple which 10 is being operated upon, the roll 17 functioning as a carrier to decrease the span or distance between the nips that the fibers must be carried without support in this operation.

By this arrangement it is found that a yarn of 15 better quality having greater strength is provided and the structure is much simplified by reason of its operating parts.

The foregoing description is directed solely towards the construction illustrated, but I desire it 20 to be understood that I reserve the privilege of resorting to all the mechanical changes to which the device is susceptible, the invention being defined and limited only by the terms of the appended claims.

25 I claim:

1. An apparatus for drafting textile fibers comprising a group of rolls including upper and lower

front draft rolls, a lower driven back roll and a driven roller bearer roll parallel and closely adjacent thereto, and a trunnionless upper back draft roll engaging said lower back roll and roller bearer roll, said back and said roller bearer rolls being of substantially equal diameters with means on the ends thereof engageable by a driver element for rotating said rolls at equal revolutions per minute to produce equal surface velocities.

2. An apparatus for drafting textile fibers comprising a group of rolls including upper and lower front draft rolls, a lower driven back roll and an upper trunnionless back roll having a reduced central portion providing shoulders to 10 be engaged for maintaining the trunnionless roll 15 in proper position relative to said other rolls.

3. A trunnionless drafting roll for textile fibers comprising two spaced leather covered sections for engaging the work, an intermediate section 20 between said leather covered sections of a diameter less than said leather covered sections, and a recess of a width less than said intermediate section in said intermediate section of still lesser diameter to receive weight supporting means and 25 to provide shoulders to locate said means.

CHARLES MORTON.
